UNITED STATES PATENT OFFICE.

ETTA L. JENKINS, OF NEW YORK, N. Y., ASSIGNOR TO THE BUTTERICK PUBLISHING COMPANY, (LIMITED,) OF SAME PLACE.

DESIGN FOR A GIRL'S COSTUME.

SPECIFICATION forming part of Design No. 17,849, dated November 1, 1887.

Application filed September 21, 1887. Serial No. 250,344. Term of patent 3½ years.

To all whom it may concern:

Be it known that I, ETTA L. JENKINS, of the city, county, and State of New York, have invented and produced a new and original 5 Design for a Pattern of a Girl's Costume; and I do hereby declare that the engraved prints accompanying this specification convey to any one accustomed to using paper patterns a clear understanding of how a garment made 10 up by the pattern will appear.

The design shows a high-necked waist exhibiting a full puff extending about the neck and shoulders and forming loose folds down the center of the front, a low-necked waist that

displays its fronts separated all the way down 15 and shaping points at their lower front corners, a full-gathered skirt depending from the body, a standing collar, and coat-sleeves with full double puffs above the elbows.

What I claim as my invention, and desire to 20 secure by Letters Patent, is—

The design for a girl's costume, as shown in the engraved prints accompanying this specification.
